DESIGN FOR A TEXTILE FABRIC OR SIMILAR ARTICLE

Gotel Canelstein, New York, N. Y.

Application November 29, 1939, Serial No. 88,547

Term of patent 3½ years

To all whom it may concern:

Be it known that I, Gotel Canelstein, a citizen of the United States and residing in the Borough of Manhattan, in the city, county, and State of New York, have invented a new, original, and ornamental Design for a Textile Fabric or Similar Article, of which the following is a specification, reference being had to the accompanying drawing, forming part thereof, wherein the drawing is a plan view of a textile fabric or similar article showing my new design.

I claim:

The ornamental design for a textile fabric or similar article, substantially as shown.

GOTEL CANELSTEIN.
